US0D1072523S

(12) **United States Design Patent** (10) **Patent No.:** **US D1,072,523 S**
(45) **Date of Patent:** **** Apr. 29, 2025**

(54) **BOARD CUSHION**

(71) Applicant: **ROSWELL CANADA INC.**, Acheson (CA)

(72) Inventor: **Derrick Wilson**, Edmonton (CA)

(73) Assignee: **ROSWELL CANADA INC.** (CA)

(**) Term: **15 Years**

(21) Appl. No.: **29/854,807**

(22) Filed: **Sep. 28, 2022**

(51) LOC (15) Cl. **06-04**

(52) U.S. Cl. **USPC D6/552**

(58) **Field of Classification Search**

USPC D6/552, 317-319, 513-514; D12/406-414; D32/35, 58

CPC B63B 34/67; B63B 32/83; B62J 7/06

(57) **CLAIM**

The ornamental design for a board cushion as shown and described.

DESCRIPTION

FIG. 1 is a front, left side, top perspective view of a board cushion of the present design;

FIG. 2 is a front, right side, top perspective view thereof;

FIG. 3 is a front view thereof;

FIG. 4 is a rear view thereof;

FIG. 5 is a left side thereof;

FIG. 6 is a right side view thereof;

FIG. 7 is a top view thereof; and,

FIG. 8 is a bottom side view thereof.

Any broken lines depict portions of the board cushion that form no part of the claimed design.

1 Claim, 8 Drawing Sheets
